UNITED STATES PATENT OFFICE.

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE.

PRINTING AND DELIVERY MECHANISM.

Application filed June 11, 1927. Serial No. 198,108.

Machines designed especially for printing and delivering loosely woven or light fabrics such as burlap or cotton often "choke up" because of the tendency of the material to wrinkle. This frequently requires the machine to be stopped and the printing mechanism to be "backed up" for removing the "choke". Therefore, some means must be employed whereby the printing mechanism may be disconnected from and reconnected to the delivery mechanism only when in their proper relation to each other.

The object of this invention is to provide novel means whereby the machine may be stopped at any point in its cycle and the printing mechanism disconnected from the delivery mechanism so that the printing mechanism can be moved to remove the "choke", or for any other purpose, said means requiring the bringing back of the printing mechanism into its proper relation to the delivery mechanism before the two mechanisms can be reconnected.

This invention more particularly includes a structure in which a clutch is provided in the driving connection between two mechanisms, which clutch is operated by a lever for disconnecting and reconnecting the two mechanisms, a lever controlling member also being provided, which member is frictionally mounted on a cylinder shaft of the printing and manually rotatable into position to permit the clutch operating lever to be manipulated to disconnect the two mechanisms while they are still in their proper relation to each other and requiring the printing mechanism to again be brought back into its proper relation to the delivery mechanism before the clutch operating lever can be operated to reconnect the mechanisms.

A practical embodiment of my invention is represented in the accompanying drawings, in which

Fig. 1 represents a diagrammatic side view of the connected printing and delivery mechanisms.

Fig. 2 represents an enlarged detail side view showing the parts in full lines in the positions they assume when the hand wheel has been moved into position to permit the operating lever to be moved to disconnect the two mechanisms; and in dotted lines in the positions the parts assume when the operating lever has been moved to disconnect the two mechanisms.

Fig. 3 represents a detail plan view of the same.

The printing mechanism is herein shown as comprising the first and second printing couples 1, 2 and 3, 4. The delivery mechanism is herein shown as comprising an endless delivery carrier 5. The driving connection between the printing mechanism and the delivery mechanism is shown as comprising a shaft 6 connected at one end to the impression cylinder 2 of the first printing couple through the clutch 7, 8 and train of gears 9, 10, 11, 12 and at its other end to the delivery mechanism through the train of gears 13, 14, 15, 16, 17. The coacting rotary cutters for severing the sheets from the web are represented by 18 and 19.

The member 8 of the clutch which carries the gear 9 is loosely mounted on the shaft 6 and the member 7 of the clutch is slidably keyed on said shaft. This clutch is utilized for disconnecting and reconnecting the printing mechanism from and to the delivery mechanism. The clutch operating lever is pivoted at 20, one arm 21 being connected to the movable clutch member 7, another arm 22 being utilized as a handle and a third arm 23 being connected to one end of a rod 24, the opposite end of which rod is bifurcated to slidably embrace the shaft 25 of the cylinder 1 of the first printing unit.

A hand wheel 26 is frictionally mounted upon the form cylinder shaft 25 so that the hand wheel may be manually rotated on said shaft. This hand wheel is provided with a circular flange 27 which has an opening 28 therethrough. The rod 24 of the clutch operating lever is provided with a stud 29 which is located within the hand wheel flange 27 when the clutch is closed and the printing and delivery mechanisms are operatively connected, so that the lever cannot be operated until the hand wheel is rotationally adjusted to bring the opening 28 in the circular flange 27 opposite the stud 29. A suitable keeper 30 engages the handle arm 22 of the clutch operating lever to hold the lever in its different positions.

In operation: When a "choke" or other contingency arises, the machine is stopped. The hand wheel 26 is then turned on its cylinder shaft 25 until the opening 28 through the circular flange 27 is brought opposite to the stud 29 on the rod 24. This will permit the clutch operating lever to be manip-

ulated to withdraw the stud 29 from within the flange and to withdraw the clutch member 7 from its engagement with the clutch member 8, thereby disconnecting the printing mechanism from the delivery mechanism. The printing mechanism may then be "moved" to remove the "choke," or for any other purpose. The printing mechanism is then returned to its original position in proper relation to the delivery mechanism by bringing the opening 28 through the flange 27 of the hand wheel 26 opposite the stud 29 on the rod 24 of the clutch operating lever. The clutch operating lever can then be moved to insert the stud 29 within the circular flange 27 and bring the clutch member 7 into engagement with the clutch member 8 to reconnect the printing mechanism to the delivery mechanism. The machine may then be started.

From the above description it will be seen that I have provided means whereby the printing mechanism may be stopped at any point in its cycle and disconnected from the delivery mechanism, said means requiring the printing mechanism to be brought back into its proper relation to the delivery mechanism before it can be reconnected thereto.

The "throw-out" means herein described is not only useful for the ready elimination of "chokes" but is also useful for permitting the printing mechanism to be disconnected from the delivery mechanism while "making-ready" and for mounting the plates, or for any other purpose.

While I have referred particularly to the application of this invention to machines for printing and delivering loosely woven or light fabrics it is to be understood that this invention is well adapted for use in machines for printing and delivering in general.

It is evident that various changes may be resorted to in the construction, form and arrangement of the several parts without departing from the spirit and scope of my invention; hence, I do not intend to be limited to the particular embodiment herein shown and described, but

50 What I claim is:—

1. A printing mechanism, a delivery mech-

anism, their driving connection, and means manually movable to permit the disconnection and reconnection of said mechanisms only when in their proper relation to each other. 55

2. A printing mechanism, a delivery mechanism, their driving connection, means for disconnecting and reconnecting said mechanisms, and a member manually movable to permit the operation of said means only when the mechanisms are in their proper relation to each other. 60

3. A printing mechanism, a delivery mechanism, their driving connection including a clutch, a clutch operating lever for disconnecting and reconnecting said mechanisms, and a lever controlling member movable into position to permit the operation of said lever only when the mechanisms are in their 70 proper relation to each other. 65

4. A printing mechanism, a delivery mechanism, their driving connection including a clutch, said printing mechanism including a cylinder shaft, a clutch operating lever for disconnecting and reconnecting said mechanisms, and a lever controlling member frictionally mounted on said cylinder shaft and manually movable into position to permit the operation of said lever only when the 80 mechanisms are in their proper relation to each other. 75

5. A printing mechanism, a delivery mechanism, their driving connection including a clutch, said printing mechanism including a cylinder shaft, a clutch operating lever for disconnecting and reconnecting said mechanisms, a rod attached to said lever and slideable on said shaft, a stud on said rod, and a hand wheel frictionally mounted on said 90 shaft and provided with an annular flange engaging said stud, said flange having an opening arranged to be brought into position to release said stud for permitting the operation of the lever only when the said 95 mechanisms are in their proper relation to each other.

In testimony, that I claim the foregoing as my invention, I have signed my name this 9th day of June, 1927.

HOWARD M. BARBER.
